HEDDLE BAR SUPPORT

Frederick M. Suchke, Atlanta, Ga., assignor to Pioneer Heddle and Reed Company, Incorporated, Atlanta, Ga., a corporation of Georgia

Application October 31, 1952, Serial No. 318,113

11 Claims. (Cl. 139—92)

The present invention relates to heddle bar supports useable in heddle frames to support the heddle bars which in turn carry a plurality of heddles.

A primary object of the present invention is to provide a support or hook which will support adequately a heddle bar intermediate its ends throughout the continuous operative cycles of the heddle frame and at the same time not suffer dislodgement or displacement thus interfering with the normal operation of the loom.

Another object of the invention is the provision of a support or hook for the heddle bar so constructed and arranged that it may move longitudinally in the heddle frame and along the heddle bar with a minimum of friction and avoid pinching or twisting which would preclude free travel of the support.

A further object is the provision of a support or hook which is readily adaptable without change of its structure for use in single or duplex heddle frames.

In general, the support or hook for the heddle bar is arranged for mounting and travel upon an auxiliary bar carried in the heddle frame and comprehends a horizontal portion which embraces in part the auxiliary bar and a vertical leg which also embraces in part the auxiliary bar and the heddle bar. The structural features of the support or hook comprehends a disposition of the major area of the hook to one side of the auxiliary and heddle bars and at the same time diminishing materially the presence of sharp corners and protuberances of like character which serve to pick up and retain lint and other deleterious material.

In utilizing the support for use in standard duplex heddle frames the surfaces of greater area are preferably positioned in opposed relation with sufficient clearance between the surfaces of each support to assure clearance in their movement or travel along the auxiliary and heddle bars. Since the likelihood of these surfaces to catch lint and other material is substantially reduced it follows that the likelihood of accumulating such material between the supports when they occupy opposing positions on their respective auxiliary bars is correspondingly reduced. The areas of the support which appear on the other or opposite sides of the bars are minor in extent and embrace those portions of the support selected to retain the support upon the auxiliary bar and to carry the heddle bar.

The support is fashioned with a horizontal and vertical leg portion lying in the main on one side of the auxiliary bar and the horizontal leg adjacent its opposite ends is bent or turned at an angle so as to cross and rest upon the outer edge of the auxiliary bar thereby positioning ends of reduced area of the horizontal leg on the opposite side of the auxiliary bar. The vertical leg of the support is slotted and formed with a lug arranged to receive and embrace the inner portions of the opposite side and inner edge of the auxiliary bar. The result of this construction is the provision of a series of bearing surfaces of small area each serving to retain the support for easy sliding movement upon the auxiliary bar, the

2

avoidance of binding and pinching and at the same time restrain such movements of the support as would dislodge it from its correct position on the auxiliary bar. The inner portion of the vertical leg of the support is slotted in such a way as to provide an open hook for the reception and support of the heddle bar and for sliding movement along said bar.

The invention will now be described in detail, reference being had to the accompanying drawings wherein corresponding parts are identified by corresponding marks of reference and wherein—

Fig. 1 is a side view partly broken away of a single heddle frame and its associated parts showing the support or hook for the heddle bar applied thereto.

Fig. 2 is an end view of Fig. 1.

Fig. 3 is a section on the line 3—3 of Fig. 1.

Fig. 4 is a section on line 4—4 of Fig. 1.

Fig. 5 is a detailed side view of the support or hook for the heddle bar, viewed from a side opposite to that shown in Fig. 1.

Fig. 6 is a plan view of Fig. 5.

Fig. 7 is a vertical transverse section through the support shown in Fig. 5.

Fig. 8 is an integral blank struck from sheet metal which may be used to form the support or hook.

Figs. 9 and 10 are views similar to Figs. 5 and 6 respectively showing a slightly different vertical leg of the support.

Fig. 11 is a detail view showing means for adjustably securing the bracket supporting the auxiliary bar to the wooden rail of the frame.

Fig. 12 is a side view partly broken away showing the application of the hook or support to a duplex heddle frame.

Fig. 13 is an enlarged end view of the upper part of Fig. 12.

Fig. 14 is a section on the line 14—14 of Fig. 12.

In Fig. 1 there is shown a single heddle frame fashioned with top and bottom wooden rails 1 and dual metallic end pieces 2, the opposite ends of which are turned at right angles and fastened to the ends of the wooden rails. Heddle bars 3 spaced from the rails 1 carry the heddles 4 and the opposite ends of the bars 3 penetrate the end pieces 2 where they are detachably secured in position by the spring clips 5, carried by the end pieces, entering openings 6 in the heddle bars. The construction just described is old and extensively used in the art.

Since the upper and lower sections of the heddle frame and the parts associated therewith are identical but assume reversed positions, it will suffice to describe the invention with relation to the upper half or section of the heddle frame.

Between the wooden rail 1 and the adjacent heddle bar 3 and spaced from each of them there is positioned an auxiliary bar 7 which may extend continuously throughout the length of the frame with each of the bar carried in the end pieces. These bars may be shorter in length with their ends supported by the wooden rail 1. In any event a support or hook generally designated 8 is arranged to be movably or slidably carried by the auxiliary bar 7 to support the heddle bar 3 and in turn the heddles 4. The support 8 can be conveniently fashioned as a single or integral piece by striking the same from sheet metal in the form shown in Fig. 8 and then swaging it to the desired shape. It may also be forged or cast to shape with its contact surfaces machined or ground if desired.

The support comprehends a horizontal leg 10 and a centrally positioned vertical leg 11 extending inwardly therefrom. When fashioned from sheet metal it is desirable to bead or swage the material of the vertical leg in a small arc about its vertical center line A—A so

as to form the vertical spaced sections 12. At the same time the horizontal leg may be swaged vertically in alignment with the center line of the vertical leg as at 13 so as to reinforce the horizontal leg against deformation. This construction is shown in Figs. 5 and 6. Instead of arranging the sections 12 one spaced from the other they may be brought together as shown in Figs. 9 and 10 and spot welded.

As shown in Fig. 5 the outer edge 14 of the horizontal leg 10 may be straight and the inner edges 15 thereof beginning at the junction with the vertical leg are inclined outwardly on each side of the vertical leg to form the horizontal surfaces or steps 16 defined by the shoulders 17 of the end lugs 18. Near each outer end of the horizontal leg and in the region of the horizontal surfaces 16 the leg is bent as at 20, so as to overlie the outer edge of the auxiliary bar 7 and to offset or place the lugs 18 out of the vertical plane of the main body portion of the leg to a position where a side surface of each lug will engage an outer part of the side surface of the auxiliary bar opposite to the side of the bar nearest the main body portion of the leg, as shown in Fig. 6. The bent sections 20 of the leg in traversing the outer edge of the auxiliary bar brings the horizontal surfaces 16 into position to form widely spaced bearings for the outer ends of the horizontal leg contacting with the outer edge of the auxiliary bar.

Each of the sections 12 of the vertical leg 11, whether spaced apart as shown in Figs. 1, 5 and 6 or brought together and united as shown in Figs. 9 and 10, is slotted adjacent its outer end as at 21 and formed with a lug 22. The slot 21 and lug 22 are shaped and arranged so as to permit the support to embrace the auxiliary bar and slide freely thereon as shown in Fig. 3 where it will be observed that the lugs 18 at the ends of the horizontal leg 10 and the lugs 22 of the vertical leg sections 12 lie on the same side of the auxiliary bar with an apparent space 22a between them. The inner ends of the sections 12 of the vertical leg are slotted as at 23 and provided with lugs 24 to form an open hook to receive the heddle bar 3.

To prevent the distortion of the auxiliary bar, which may arise due to a bowing of the wooden rails especially in the case of frames of extended length, one or more brackets 30 are employed having their outer ends adjustably attached to the wooden rail 1 and their inner ends attached to the auxiliary bar 7 in the manner about to be described. The outer end of the bracket 30 is bent at an angle substantially to form the horizontal element 31. This element overlies a metal plate 32 affixed to a rabbeted section of the outer portion of the rail by the screws 33. The plate 32 is tapped to receive one or more screws 34 provided with a grooved head 35. The horizontal element 31 is slotted as at 36 to permit the element 31 to enter the groove. Screws 37 near the opposite edges of the element 31 pass through the plate 32 and enter the rail 1. By adjusting the screws 34 and 37 the bracket may be moved inwardly or outwardly of the wooden rail and maintained in its adjusted position and thus hold the auxiliary bar 7 straight.

The vertical element 38 of the bracket 30 preferably is set in a rabbet on one side of the wooden rail so as to lie flush with it and is slotted as at 40 to receive a screw 41 entering the rail so that under all adjustments of the bracket 30 it will remain seated in the rabbet. The vertical element 38 of the bracket extends inwardly of the frame and to one side of and spaced from the vertical plane of the auxiliary bar 7 and is attached to a side face of the auxiliary bar intermediate its inner and outer edges by the spacer 42 and rivets 43 as shown in Fig. 4. The dimensions of the spacer should be such as to permit the widely spaced lugs 18 at the opposite ends of the horizontal leg and the lugs 22 on the vertical leg of the support to pass the spacer in the travel of the support along the auxiliary bar and at the same time permit

the lugs to contact with the auxiliary bar as shown in Fig. 3.

In Figs. 12, 13 and 14 there is shown a duplex heddle frame wherein there is included two auxiliary bars 7 and two heddle bars 3, the latter held in the end pieces of the frame by spring clips 5. Each heddle bar carries its usual set of heddles 4. Brackets 30 are mounted on the opposite faces of the rail 1 and each are mounted for adjustment as previously described. Each bracket extends inwardly and is attached to the outside face of its complementary auxiliary bar in the manner previously described. Each auxiliary bar carries its individual support or hook 8 in the manner shown in Fig. 14 so that major areas of the support are adjacent each other and since these areas are relatively smooth and not broken or interrupted by openings, lugs, etc., the tendency to collect lint or other material on the inside of or between the hooks, where accessibility may be difficult, is substantially reduced. The bifurcations, lugs, etc., formed in and on the horizontal and vertical legs of the hooks are thus located outwardly of each other (in a transverse plane) and thus toward the outer sides of the frame, where lint and other material, if collected, may be readily removed. This arrangement also provides for the ready removal of the heddle bars.

The invention as herein described lends itself readily to standard or common forms of heddle frames and especially those embodying metallic closed eye heddles, since the heddle bar supports are free to slide along the auxiliary and heddle bars thereby permitting the heddles to move laterally and freely and find their positions in respect to their individual warp threads. By positioning the supports with the lugs 24 outwardly of the duplex frame in a transverse plane as shown in Figs. 12, 13 and 14 ready removal of the heddle bars may be had by moving one or more of the heddle bar supports toward the end of the frame and then springing the heddle bars at its central zone laterally or in a direction away from the sides of the frame whereupon the heddle bar ends will clear the inside of the end pieces and then may be lifted clear of the heddle bar supports.

What is claimed is:

1. In a heddle bar support, the combination with a rail of a heddle frame and a heddle bar, of an auxiliary bar extending substantially parallel to said heddle bar and spaced between said bar and said rail, a heddle bar support, slidably mounted on said auxiliary bar, having a vertical leg and a horizontal leg centrally united to the vertical leg, said horizontal leg having its major area providing a flat face adapted to lie to one side of and contact with the adjacent side face of the auxiliary bar, said horizontal leg having an edge of the same thickness uppermost throughout its length, said horizontal leg to each side of the vertical leg being provided with spaced bearing edges overlying the outer edge of said auxiliary bar and terminating at each end in lugs engageable with the outer portion of the opposite face of the auxiliary bar, said vertical leg being slotted and provided with at least one lug adapted to engage the inner portion of said opposite face of the auxiliary bar, said vertical leg, adjacent its inner end being slotted and provided with a lug to form an open hook for the reception of the heddle bar.

2. In a heddle bar support, the combination with a rail of a heddle frame and a heddle bar, of an auxiliary bar extending substantially parallel to said heddle bar and spaced between said bar and said rail, a heddle bar support, slidably mounted on said auxiliary bar, having a vertical leg and a horizontal leg centrally united to the vertical leg with the major portion of the horizontal leg providing a side face located adjacent one side of and contact with said auxiliary bar, said horizontal leg having an edge of the same thickness uppermost throughout its length, said horizontal leg to each side of the vertical leg being provided with spaced bearing edges formed by

bending each outer portion of said horizontal leg across the outer edge of the auxiliary bar for engagement therewith, each end portion of the horizontal leg terminating in lugs adapted to engage the outer portion of a side of the auxiliary bar opposite to said first named side, said vertical leg being slotted and provided with at least one lug adapted to engage the inner portion of said opposite face of the auxiliary bar, said vertical leg adjacent its inner end being slotted and provided with a lug to form an open hook for the reception of the heddle bar.

3. In a heddle bar support, the combination with a rail of a heddle frame and a heddle bar, of an auxiliary bar extending substantially parallel to said heddle bar and spaced between said bar and said rail, a heddle bar support including horizontal and vertical leg portions with major portions of the metal of the horizontal leg providing a side face adapted to lie adjacent one side face of and contact with said auxiliary bar, said horizontal leg portion having an edge of the same thickness uppermost throughout its length, the inner edge of said horizontal leg portion to each side of the vertical leg tapering outwardly to a flat inner edge substantially coincident with the outer edge of the auxiliary bar, said flat edge traversing said outer edge, lugs formed at each outer end of the horizontal portion adapted to engage an outer portion of the face of the auxiliary bar opposite said first named side face, said vertical leg being slotted and provided with at least one lug adapted to engage the inner portion of said opposite face of the auxiliary bar, said vertical leg adjacent its inner end being slotted and provided with a lug to form an open hook for the reception of the heddle bar.

4. In a heddle bar support, the combination with a rail of a heddle frame and a heddle bar, of an auxiliary bar extending substantially parallel to said heddle bar and spaced between said bar and said rail, a heddle bar support provided with a horizontal leg having an edge of the same thickness uppermost throughout its length and having an intermediate portion providing a side face arranged to lie adjacent and contact with a side face of said auxiliary bar and portions adjacent each end of the leg turned and crossing edgewise the outer edge of said auxiliary bar, a lug at each end of the horizontal leg engageable with the outer portion of the side face of the auxiliary bar opposite said first named side face, a vertical leg integral with the central portion of the horizontal leg and extending inwardly therefrom, said vertical leg being slotted and provided with at least one lug adapted to engage the inner portion of said opposite face of the auxiliary bar and having its inner end slotted and provided with a lug to form an open hook for the reception of the heddle bar.

5. In a heddle bar support, the combination with a rail of a heddle frame and a heddle bar, of an auxiliary bar extending substantially parallel to said heddle bar and spaced between said bar and said rail, a heddle bar support provided with a horizontal leg having an edge of the same thickness uppermost throughout its length and having an intermediate portion providing a side face arranged to lie adjacent and contact with a side face of said auxiliary bar, portions adjacent each end of the leg turned and crossing edgewise the outer edge of said auxiliary bar, a lug at each end of the horizontal leg engageable with the outer portion of the side face of the auxiliary bar opposite said first named side face, a vertical leg integral with the central portion of the horizontal leg with the metal of the vertical leg bent upon itself to form inwardly extending spaced sections, each section being similarly slotted and provided with a lug adapted to engage the inner portion of said opposite face of the auxiliary bar and having its inner end slotted and provided with a lug to form an open hook for the reception of the heddle bar.

6. In a heddle bar support, the combination with a

rail of a heddle frame and a heddle bar, of an auxiliary bar extending substantially parallel to said heddle bar and spaced between said bar and said rail, a heddle bar support provided with a horizontal leg having an edge of the same thickness uppermost throughout its length and having an intermediate portion providing a side face arranged to lie adjacent and contact with a side face of said auxiliary bar, portions adjacent each end of the leg turned out of the vertical plane of said intermediate portion and crossing edgewise the outer edge of said auxiliary bar, a lug at each end of the horizontal leg displaced from the vertical plane of the intermediate portion and engageable with the outer portion of the side face of the auxiliary bar opposite said first named side face, a vertical leg integral with the central portion of the horizontal leg with the metal of the vertical leg bent upon itself to form inwardly extending spaced sections, each section being similarly slotted and provided with a lug adapted to engage the inner portion of said opposite face of the auxiliary bar and having its inner end slotted and provided with a lug to form an open hook for the reception of the heddle bar.

7. In a duplex heddle frame, the combination with a heddle frame including a rail, two heddle bars adjacent said rail and spaced therefrom and transversely spaced from each other, of auxiliary bars between said rail and each of said heddle bars and spaced therefrom, at least one heddle bar support, slidably mounted on each auxiliary bar, provided with a horizontal leg having an intermediate portion fashioned to lie adjacent to the side face of an auxiliary bar opposing the side face of the other auxiliary bar, each horizontal leg adjacent its end portions being turned transversely outward of the heddle frame to cross and engage the outer edges of each auxiliary bar, lugs at the end of each horizontal leg engageable with the outer portion of the side face of each auxiliary bar facing transversely outward of the heddle frame, a vertical leg individual to each horizontal leg and integral with the central portion of the latter and extending inwardly therefrom between opposing faces of each auxiliary bar, each of said vertical legs being slotted and provided with at least one lug adapted to engage the inner portion of the side face of each auxiliary bar transversely outward of the frame, each of said vertical legs adjacent its inner end being slotted and provided with a lug engageable with the outer edge and side face of the respective heddle bar transversely outward of the frame.

8. In a heddle bar support, the combination with a rail of a heddle frame and a heddle bar, of an auxiliary bar extending substantially parallel to said heddle bar and spaced between said bar and said rail, a heddle bar support provided with a horizontal leg having an intermediate portion arranged to lie adjacent a side face of said auxiliary bar and having its central portion vertically swaged to reinforce said leg, portions adjacent each end of the leg being turned and crossing the outer edge of said auxiliary bar, a lug at each end of the horizontal leg engageable with the outer portion of the side face of the auxiliary bar opposite said first named side face, a vertical leg integral with the central portion of the horizontal leg with the metal of the vertical leg bent upon itself in alignment with the vertical swaging in the horizontal leg to form inwardly extending spaced sections, each section being similarly slotted and provided with a lug adapted to engage the inner portion of said opposite face of the auxiliary bar and having its inner end slotted and provided with a lug to form an open hook for the reception of the heddle bar.

9. The combination with a rail of a heddle frame, of an auxiliary bar supported at its ends within said frame, a plate recessed and affixed to the outer edge of said rail, a bracket having an outer horizontal element provided with a bifurcation extending laterally above said plate, a screw threaded into said plate and having a head grooved to receive the walls of the element defining said bifurca-

7
tion, screws on opposite sides of the first named screw passing through said plate and entering said rail, said bracket having a vertical element united to said horizontal element and extending inwardly of the frame in a plane spaced from the vertical plane of the auxiliary bar with the inner end of said vertical element spaced from a side face of the auxiliary bar and attached thereto at a point intermediate the outer and inner edges of the auxiliary bar and means for slidably connecting said vertical element to a side of said rail.

10. The combination with a rail of a heddle frame, of heddle supporting means carried within said frame, a plate recessed and affixed to the outer edge of said rail, a bracket having an outer horizontal element provided with a bifurcation extending laterally above said plate, a screw threaded into said plate and having a head grooved to receive the walls of the element defining said bifurcation, screws on opposite sides of the first named screw passing through said plate and entering said rail, said bracket having a vertical element united to said horizontal element and extending inwardly of the frame in a plane spaced from the vertical plane of the heddle supporting means with the inner end of said vertical element spaced from a side face of the heddle supporting means and attached thereto at a point intermediate the outer and inner edges of the heddle supporting means, and means for slidably connecting said vertical element to a side of said rail.

11. The combination with the rail of a duplex heddle frame, bars for supporting heddles carried at their ends within said frame, brackets located on opposite faces of said rail having outer horizontal elements turned inwardly toward each other and provided with bifurcations, screw means within said bifurcations engaging said elements for adjusting said brackets, said brackets each having a vertical element united to said horizontal element and extending inwardly of the frame in a plane spaced from the plane of each of the bars for supporting the heddles with the inner end of said vertical element spaced from the side face of the bar for supporting the heddles and attached thereto at a point intermediate the outer and inner edges of the bar supporting the heddles, and means for slidably connecting each of said vertical elements to opposite sides of said rail.
